Joseph Melzer INVENTOR.

BY N. S. Anstutz.

ATTORNEY,

UNITED STATES PATENT OFFICE.

JOSEPH MELZER, OF CLEVELAND, OHIO, ASSIGNOR TO THE OSBORN-MORGAN COMPANY, OF CLEVELAND, OHIO, A CORPORATION OF NEW JERSEY.

ELECTRIC-ARC LAMP.

SPECIFICATION forming part of Letters Patent No. 742,705, dated October 27, 1903.

Application filed April 10, 1901. Serial No. 55,193. (No model.)

To all whom it may concern:

Be it known that I, JOSEPH MELZER, a citizen of Austria-Hungary, residing at Cleveland, in the county of Cuyahoga and State of Ohio, have invented certain new and useful Improvements in Electric-Arc Lamps, of which the following is a specification, reference being had therein to the accompanying drawings.

10 My invention relates to improvements in electric-arc lamps, and it appertains to the features hereinafter set forth in the specification, illustrated in the accompanying drawings, and more especially pointed out in the annexed claims.

15 The object of my invention is to produce an arc-lamp that shall be economical of construction, have the fewest possible number of parts, and produce illumination at the highest efficiency. Coextensive with the features enumerated, also to provide the simplest operating mechanism, that lends itself to steadiness of arc and ease of trimming.

20 With these ends in view I illustrate in the figures of the accompanying drawings such instances of adaptation as will show the fundamental principles of the invention without limiting myself to the specific construction instanced in the drawings.

25 Figure 1 is an elevation in vertical section. Fig. 2 is a plan view in the vicinity of the clutch. Fig. 3 is a plan view of the means shown in the drawings for removably securing the inner globe. Fig. 4 is a diagrammatic representation of the circuit connections applicable to the instance of adaptation shown in the drawings. Fig. 5 is a perspective view of the carbon-cap. Fig. 6 is an enlarged section of the magnet.

30 This form of lamp has the controlling-magnet suspended from the supporting-head, which is utilized in hanging up the lamp, to ceilings, &c., and the casing is also supported by this head. The rheostat on low voltage circuits the steadyng resistance is placed under a projection of the casing. When potentials, as two hundred and twenty volts, &c., are used, the resistance is placed in a separate canopy, which may be a part of the usual suspending-rod.

35 The means for fastening the inner globe are

unique in that they allow of a quick removal of the globe and a ready fastening thereof without any supporting means whatever being used at the bottom thereof.

55

As supporting-head B carries an insulator b, from which the lamp is suspended. It is held in a removable manner upon the magnet-head C by receiving a threaded bolt c, projecting therefrom. This projection has formed thereon an annular groove c', into which a locking-screw b' sets, and thus prevents the lamp from receiving injury on account of accidental separation of the head from the magnet.

60

Upon the magnet-head C is placed an insulating-bushing c², which insulates the casing-hood D from the projection c. The hood is flanged upwardly around c², so as to receive and hold an insulating-washer d in position while the parts are being assembled. The head B clamps washer d between itself and the casing-hood D.

65

The usual protected lamp-terminals are placed on the casing-hood D, as follows, viz: A boss or projection d' is secured to the hood 70 for each terminal, a hole of some size is made therethrough, and insulating-bushings d² are set therein on opposite sides thereof. A terminal cap d³, having an annular depending apron d⁴, is secured on the uppermost bushing d² by means of a suitable screw d⁵, and terminal screws d⁶ are placed in the caps for holding the terminal wires.

75

A permeable head C, that has a slightly-counterbored cylindrical body c³ formed integral with the flange portion c⁴, forms the magnet spool-head. The portion c³ passes about half-way through a non-permeable core-tube c⁵, and a non-permeable guide-tube c⁶ projects from the counterbored end of c³. 80 This tube serves as an armature-guide. The lower magnet-head C' is similar to the head C. A short hub c⁷ passes into the tube c⁵. A hole is formed in this hub somewhat larger than the armature to insure against the actual contact between these parts. As will be seen from the drawings, an open space is left between c³ and c⁷. This space is spanned by the armature C³. The guide-tube c⁶ also projects into this space. The armature C³ is 85 made of highly-permeable material, the same as heads C and C' and their core projections

90

95

100

*c*³ and *c*⁷. A slot *c*⁸ is formed in the armature, and a carbon and clutch tube *E* is threaded into the lower end of the armature. Any suitable non-magnetic material is secured to the upper face of the armature to prevent its sticking to the counterbored portion of the projection *c*³, or an ordinary brass plug may be secured in *c*³ for the same purpose.

5 A carbon and clutch tube *E* is slotted lengthwise thereof at *e*. This slot forms a guide for a carbon-cap *F*, which slips upon the upper end of a carbon *f*. It is also provided with a terminal screw that serves to hold one end of a flexible cable *f*', the other end of which 10 is in circuit with the wire of the regulating-magnet, that is wound upon the tube *c*⁵ between heads *c*⁴ and *C*'.

The casing-hood *D* is secured to a central or body portion *D*' of the casing. This central portion extends above the joining-point at *D*², so as to prevent the admission of rain, &c., through ventilating-holes *D*³. At the lower end of *D*' a flaring apron *D*⁴ is formed, which joins onto *D*' at *D*⁵. The extreme bottom end of *D* is fastened to a globe-centering ring *G* by means of screws or pins. This ring *G* has a central web, and an opening is formed therein considerably larger than the carbon-tube *E*. A plate *g*, insulated from *G*, is secured 20 thereon by screws, which are also suitably insulated. This plate serves to guide the carbon-tube *E*.

30 Rheostat-insulators *H* are secured under the casing-apron *D*⁴ by means of any suitable fastenings. Through these insulators a 35 steady resistance *h* is passed. The adjacent faces of the casing are preferably covered with a lining of asbestos, so as to afford protection against the radiant heat of the rheostat.

The two rods *i* and *i*' depend from ring *G*, so as to support a gas-cap *i*². The rod *i* is insulated from *G* and *i*². It has connected therewith a binding-post *i*³ at its upper end 45 and the negative or lower carbon connection *l*⁴, which passes through the bottom of the gas-cap *i*² and is insulated therefrom by a porcelain or any other heat-resisting insulator.

Secured to the gas-cap *i*² are two or more 50 depending brackets *J*, which hold a split spring-ring *j*. This ring encircles the inner globe *K* under the flaring head or rim *k*, and by means of screw-rod *j*' and thumb-nut *J*² it is opened or closed, thereby holding or 55 loosening the inner globe, as desired. Gas-cap *i*² has formed thereon a depending flange *i*³, which forms an inner wall of an annular groove *i*⁶, in which a packing of asbestos is placed. This packing forms a cushion for 60 the inner globe *K*. The flaring walls of the gas-cap serve as reflecting-surfaces for heat and light. In the floor or bottom is formed a hole through which the upper carbon loosely passes. Rod *i*' is fastened to a boss or lug 65 of cap *i*² at its lower end and at its upper end to the ring *G*. It is not necessary that these

fastenings should be insulated. The bottom of gas-cap *i*² also serves to trip the carbon-clutch when it is necessary to feed the upper carbon. At the lower end of carbon-tube *E* the clutch is fastened. This consists of a weighted lever *l*, pivoted at *l*' to a depending bracket *l*², which is secured to the plate *L*. The lever *l* has formed therein a hole through which the carbon *f* passes. A spring *l*³ serves 70 to overcome any tendency toward vibration of the lever *l* by placing pressure upon the weighted end thereof. This lever has a lower projection *l*⁴, which strikes the floor of the gas-cap when it is necessary to feed the carbon. 75

An arc-striking limit-stop is found by fastening a threaded rod *L*' upon clutch-plate *L*. This rod extends upward through ring *G* and plate *g*, and check-nuts *L*² are placed 80 thereon. The lower one is insulated on the face which comes into contact with plate *g*. This one limits the length of the arc, and the upper one is a safety limit to the downward movement of the clutch, carbon-tube, and arc-mature. 85

The lower carbon *M* is held in place by means of the negative connection *i*' through an annular ring *i*⁷, fastened thereon, and a set-screw *i*⁸ holds the carbon in position. The 90 inner globe *K* is only open at its upper end. The outer globe *N* has the usual curved flange at the top, through which set-screws *n* hold this globe to the globe-ring *N*'. The globe-ring is held under the casing by pivoted hooks *N*², which snap over catches *n*', that are secured to the casing. Any suitable chain may be fastened to the casing and globe-ring upon which to suspend the unhooked globe and ring while the lamp is being trimmed. 95

The circuit connections are shown more especially in Fig. 4. They are as follows, viz: The current enters at + and passes to the magnet, thence via flexible cable to the carbon-cap, thence along the upper carbon across the arc to the negative carbon and via binding-post and intermediate rods to the rheostat and from thence to the negative terminal. 100

What I claim is—

1. In an electric-arc lamp, the combination 115 of permeable magnet-heads one having a permeable core projection, and a movable armature passing through the other head and into a recess in said projection, and a non-permeable core-tube on the outside of said projection and connected to the other head, substantially as set forth.

2. In an electric-arc lamp, a controlling-magnet comprising the combination of a hollow non-permeable core-tube and permeable 120 magnet-heads, one of said heads having a permeable core projection formed thereon within said tube, substantially as set forth.

3. In an electric-arc lamp, a controlling-magnet comprising in combination permeable 125 heads and a permeable core projection on one of said heads, with a movable armature adapt-

- ed to pass into the magnet through the other of said heads, and a non-permeable core-tube on the outside of said projection and secured to the last-mentioned head, substantially as set forth.
- 5 4. In an electric-arc lamp, in combination, a controlling-magnet comprising a hollow winding, a pair of heads therefor, a permeable core extension to one of said heads extending into said winding, a non-permeable guide carried by said core extension, a non-permeable core-tube passing around said extension and secured to the other head, and a movable permeable armature passing through a hole in the last-mentioned head and adapted to engage said guide, substantially as set forth.
- 15 5. In an electric-arc lamp, a controlling-magnet comprising a hollow winding, a pair of permeable heads, a permeable core projection on one of said heads extending into the hollow winding, there being a large space of high magnetic reluctance between the face of said projection and the other head, such latter head having an opening through it, in combination with a non-permeable guide within the hollow of the winding, and a movable permeable armature adapted to stand in said opening while in the control of said guide, substantially as set forth.
- 20 6. In electric-arc lamps, in combination, a bottom ring having a web, a carbon-tube passing therethrough, said carbon-tube having a longitudinal slot, a carbon-cap guided thereby, a clutch secured to the lower extremity of said carbon-tube, a rod secured to said clutch, and passing through said web, said web having an opening therefor, and adjustable stops carried by said rod on either side of said web, substantially as described.
- 25 7. In electric-arc lamps, in combination, a body, an apron thereabout, a rheostat carried beneath said apron, a globe, and members passing around said apron and adapted to support said globe from said body, substantially as described.
- 30 8. In electric-arc lamps, a controlling-magnet, a clutch, an armature-supported carbon-tube extending from the magnet to the clutch, in combination with limit-stops adjustable with respect to each other placed upon said
- 35 clutch whereby the armature movement is controlled within predetermined limits in either direction, substantially as set forth.
9. In electric-arc lamps, in combination, a gas-cap having an upwardly-flaring rim, a globe-ring having a groove, and a transverse web which combines with said flaring rim to form a basin, said web having a hole through which a carbon may pass, insulated supports for said gas-cap, a globe-holding fixture depending from said cap, and a negative terminal insulated from said cap and adapted to support a carbon, substantially as described.
- 40 10. In electric-arc lamps, in combination, a body, an apron projecting outwardly therefrom, rheostats carried beneath said apron, a globe-ring beneath said body, members which reach around said apron and which support said globe-ring, and means for supporting said globe-ring by said body, substantially as described.
- 45 11. In an electric-arc lamp, in combination, a casing-hood, a controlling-magnet carried beneath the same, a projection carried by said magnet and passing upwardly through the top of said casing-hood, a head by which said lamp is adapted to be supported, and a swivel connection between said head and said projection, substantially as described.
- 50 12. In an electric-arc lamp, in combination, a casing-hood, a controlling-magnet carried just beneath the top thereof, a head above said hood, a swivel connection between said hood and head, an armature coöperating with said controlling-magnet, a carbon-tube carried thereby, and a clutch carried by said carbon-tube, substantially as described.
- 55 13. In an electric-arc lamp, in combination, a hood, a controlling-magnet beneath said hood, a head above said hood, a swivel connection between said head and hood, means for insulating said head and hood, and an insulator carried by said head and adapted to form a suspension-point for said lamp, substantially as set forth.
- 60 95 In testimony whereof I affix my signature in presence of two witnesses.

JOSEPH MELZER.
